UNITED STATES PATENT OFFICE.

DANIEL P. DAUGHERTY, OF WORDEN, OREGON.

DOOR-SECURER.

1,220,499.

Specification of Letters Patent.

Patented Mar. 27, 1917.

Application filed August 9, 1916. Serial No. 113,920.

To all whom it may concern:

Be it known that I, DANIEL P. DAUGHERTY, a citizen of the United States, residing at Worden, in the county of Klamath, State 5 of Oregon, have invented a new and useful Door-Securer; and I do hereby declare the following to be a full, clear, and exact description of the invention, such as will enable others skilled in the art to which it 10 appertains to make and use the same.

This invention relates to a new and useful securer for holding a door closed from the interior without employing a key in the lock.

15 One of the objects of the invention is to provide an angular plate, one arm of which is provided with a lip to embed in the jamb of the door frame, with the arm between the door and the jamb, in combination with a 20 plate pivoted upon the other arm and having an overhanging spring arm, the extremity of which engages a recess of the second arm, to hold the plate overlying the door, to prevent the door from being opened.

25 In practical fields the details of construction may necessitate alterations falling within the scope of what is claimed.

The invention comprises further features and combination of parts as hereinafter set 30 forth shown in the drawings and claimed.

In the drawings:—

Figure 1 is a view in perspective of a portion of a door and the jamb, showing the securer as applied thereto, to hold the door 35 closed.

Fig. 2 is a perspective view of the door and the jamb, showing the securer applied, and the plate pivoted to one of the arms as thrown vertically, so that the door may 40 be opened.

Fig. 3 is a sectional view on line 3—3 of Fig. 1.

Fig. 4 is a view in elevation, showing the locking plate moved in such a position that 45 the extremity of the spring arm of said locking plate is about in the act of engaging a notch in one end of one of the arms of the angle plate, the other arm of which extends into the space between the edge of the door and the jamb.

Referring more especially to the drawings 1 designates an angular plate, the short arm 2 of which is designed to engage between the

edge of the door and the jamb of the frame, so that the long arm 3 engages the face 4 of 55 the frame of the door. The short arm 2 is provided with a lip 5, which is designed to embed into the jamb of the door frame, thereby preventing displacement of the angular plate when the door 6 is closed. Piv- 60 oted by means of the pivot pin 7 to the arm 3 of the angular plate 1 is a latching or locking plate 8. This plate is so pivoted to the angular plate 1, that when it is disposed as shown in Fig. 2, the door 6 may be freely 65 opened and closed, but when moved to the position shown in Fig. 1 the end portion 9 of the plate 8 will overlie the door 6, thereby preventing the same from being opened. The end portion 10 of the arm 3 of the angular plate 1 is provided with a notch 11 70 and the tapered lugs 12. The end portion 9 of the plate 8 terminates in an arched spring arm 13, the portion 14 of which extends toward the door frame, so that the extremity 75 of the portion 14 will ride over one or the other of said lugs 12 and engage the notch 11, thereby holding the plate 8 in the position shown in Figs. 1 and 3, so that its portion 9 will be held overlying the door 6. It 80 is to be noted that the angular plate 1 may be arranged in position temporarily, but the short arm 2 is provided with an aperture 15, for the reception of the screw 16, which threads into the jamb, whereby the angular 85 plate 1 may be permanently attached to the jamb. When the plate 8 is disposed as shown in Figs. 1, 2 and 3 and a pull is exerted upon the door, the same will abut the portion 9 of the plate 8, and owing to the 90 lip 5 being embedded in the jamb, the door will be prevented from being opened.

The invention having been set forth what is claimed as new and useful is:—

In a door securer, the combination of a 95 plate and an arm integral on one end thereof adapted to extend between the edge of a door and the jamb and provided with a lip to embed in the jamb, of a second plate pivoted to the first plate and adapted to overlie 100 the door to prevent the same from opening, the pivot of the second plate being arranged in such relations with the arms of the first plate, that the second plate may be disposed vertically whereby the door may 105 swing freely open, and means for locking

the second plate in a position overlying the door, said means comprising a notch in one end of the first plate, and a laterally arched spring arm at one end of the second plate, the extremity of which spring arm engages said notch to hold the second plate lying across the door.

Copies of this patent may be obtained for five cents each, by addressing the "Commissioner of Patents, Washington, D. C."

In testimony whereof I have signed my name to this specification in the presence of two subscribing witnesses.

DANIEL P. DAUGHERTY.
